GRINDING MILL

Lyle M. Barker and Evan G. Lewis, Ajo, Ariz.,
assignors to Phelps Dodge Corporation, New
York, N. Y., a corporation of New York

Application January 13, 1943; Serial No. 472,200.

8 Claims. (Cl. 241—70)

1

This invention relates to grinding mills in which the comminution of ore or other material is effected by the grinding action of a mass of moving balls, pebbles, or the like, within a rotating cylinder, and in which the comminuted material is discharged through a grated portion of the cylinder. In mills of this type the plugging of the grate openings by worn grinding media, larger particles of ore, or the like constitutes a source of considerable annoyance, necessitates loss of operating time in repeated cleaning of the grates, and results in substantial diminution of mill capacity and efficiency.

The prime object of the present invention is to provide a grated discharge portion of a grinding mill which enables ready egress of ground materials, worn grinding media, or other materials having certain maximum dimensions without the objectionable clogging tendencies exhibited in prior constructions. The invention provides a mill discharge end which fulfills this purpose in a particularly simple and effective manner; and which enables the advantages of mills of the type mentioned to be utilized fully, without interference by objectionable plugging of the discharge grates.

Other features and advantages of the invention will be hereinafter described and claimed.

In the accompanying drawing:

Fig. 1 is a fragmentary elevation, as viewed from the inside, showing a portion of the discharge end of a grinding mill embodying one form of our invention.

Fig. 2 is a fragmentary view in vertical section, taken on line 2—2 of Fig. 1.

Fig. 3 is a horizontal section, on an enlarged scale, taken on line 3—3 of Fig. 1.

Since our invention relates only to the discharge end of the grinding mill, and, as the general construction of such mills is well known to persons familiar with the art, we will describe particularly only the discharge end of the mill.

Referring to the drawing, 2 designates the cylindrical shell or main body portion of the grinding mill, and 3 the head, which closes the discharge end of said shell. Secured to said head 3 is the customary centerpiece 4, which, as shown, may include a passage 5, serving as an observation port and as a point of addition of balls or other grinding media. Said centerpiece also has formed therein a diversion passage 6 for the mill product. The shell 2 is provided with a lining 7 of suitable refractory material. A center end liner, which may be of form and material best adapted for grinding conditions, is indicated at 8; while other suitable end liners, disposed out-

wardly from said liner 8, are shown at 9 and 10. Pulp lifter elements 11 of conventional form are also shown:

In carrying out our invention, we form discharge slots, such as are shown at 12, by mounting elements 13 of rubber or other suitable resilient material in suitably spaced relationship. In the embodiment illustrated, these resilient elements 13 are mounted in cut out portions of the liners 8, 9, and 10, and are attached to and firmly maintained in position by backing plates 14 welded or otherwise suitably secured to said liners or to the discharge head 3. As shown, said backing plates 14 terminate short of the edges of the rubber elements 13 to enable flexure of said edges to the extent desired.

We furthermore, so space the liners 8, 9, and 10 with respect to each other as to form between them channels 15 of such width or form as to permit ready movement within said channels of the largest ball or other grinding member in the charge. The liners which form the channel also function to prevent direct action of any large portion of the charge of grinding members upon the rubber elements 13.

It will be understood that the cylinder 2, lining 7, head 3, centerpiece 4, liners 8, 9, and 10, and lifters 11 are suitably fastened together to rotate in unison in the operation of the mill. The lifters 11 are integral with the head 3, which is suitably secured to the cylinder 2 and centerpiece 4; while the liners 8, 9, and 10 and associated backing plates 14 are suitably fastened to the lifters 11.

In assembling said liners and associated parts, the liner 10 may first have attached thereto a rubber element 13 and a backing plate 14. The latter may be fastened to the liner by suitable bolts or by welding. Thereafter, said liner 10 may be inserted into the head 3 and secured therein by a suitably tight fit, or by welding or otherwise fastening the backing plate 14 to the lifter 11. Liner 8, after having a rubber element 13 and backing plate 14 attached thereto may then be placed in the desired position on the lifters 11 and fastened in position through said plate 14. Said liner 8 may also, as shown, have a similar plate 14' interposed between said liner and said lifter and suitably fastened thereto. Then the liner 9, after having rubber elements 13 and backing plate 14 attached thereto, is placed on the lifters 11 in the desired spaced relationship with respect to the liners 8 and 10; following which said liner 9 is secured to said lifters 11 through 55 said plate 14 in any desired manner. The cen-

terpiece 4 may then be inserted into the head 3 and secured thereto, after which said head may be secured to the cylinder 2.

In operation, the parts above described rotate in unison, and the balls or other grinding elements act upon the ore, or other material to be ground, in the cylinder 2. The comminuted particles pass through the slots 12, provided by the rubber elements 13, and thence into the spaces between the lifters 11, whence said particles are directed outwardly through the passage 6.

It will be observed not only that the plates 14 provide backing for the rubber elements 13 by extending beyond the liners, but also that said plates, by terminating short of the edges of said elements, provide for controlled flexure of said edges. Said plates may be so positioned with respect to said edges as to control flexure of the latter to the desired extent.

A ball mill equipped with a discharge end embodying our invention has been found to maintain full efficiency for a prolonged period, without interruption and without any evidence of plugging. The freedom from the necessity of periodic cleaning of grates, and the gains in capacity and efficiency resulting from the avoidance of grate clogging, are substantial and important advantages.

While we do not assert any particular theory as controlling or conclusive with respect to the advantages attained by our invention, we believe that one reason for the attainment of those advantages is the capability of the resilient elements 13 to dislodge, or feed back into the cylinder 2, oversize particles which may become momentarily lodged between said elements. In that connection, it is to be noted that the width of the slot 12 between adjacent rubber elements 13 is fixed only so long as said elements are not deformed from their original positions. The slot also has depth, i. e., that of the thickness of the rubber, and its walls are constantly parallel when in normal position. However, upon flexure of the rubber elements the width of the slot increases, and the walls diverge in the direction of deformation. Now, when a particle is presented at a slot 12 and forced against the adjacent elements 13, that particle can pass only if its minimum dimension is such that it may enter the slot under the condition of maximum slot deformation. If the forces tending to move the particle into the slot are not adequate for the purpose, the reflex of the rubber elements rejects it when the forces are removed. It is also possible that particles of certain shape may be temporarily retained in the slot and that the flexing and deformation of the rubber elements resulting from the subsequent entry of other particles accomplishes their release. But whatever may be the theory, we have found the construction illustrated to be highly effective in obviating clogging, with the consequent advantages hereinbefore referred to.

The elements 13 may be of rubber or any other material having the desired strength, flexibility, and resiliency. Fabric-reinforced rubber, conveyor-belt cover stock rubber, or the so-called "floating-stock" rubber are examples of suitable materials which may be employed.

We believe also that the provision of channels 15 of such width or form as to permit ready movement within them of the largest ball, or other element in the grinding charge, augments the effectiveness of the invention by enabling grinding elements to act upon particles in the channels adjacent the slots.

The backing plates 14 may be of rigid material such as steel, or of material resilient and flexible in character, such as conveyor belting.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

We claim:

1. Grinding mill discharge means comprising members defining a channel, a plurality of resilient elements mounted on said members at the base of said channel and defining a slot, and backing means extending beyond said members over portions of said resilient elements and terminating short of the slot defining edges of said elements.

2. Grinding mill discharge means comprising members defining a channel in communication with the grinding chamber of the mill, resilient elements in spaced relationship defining a slot at the base of said channel, and backing means for said resilient elements, said backing means extending over portions of said elements but terminating short of the slot forming edges of said elements.

3. Grinding mill discharge means comprising members defining a channel in communication with the grinding chamber of the mill, said channel being of such form as to permit free movement of grinding elements within it, resilient elements disposed at the base of said channel and defining a slot at said base, and backing means extending into overlapping relation with portions of said resilient elements and with portions of said channel, said backing means terminating short of the slot-defining edges of said elements.

4. Discharge means for a grinding mill of the type comprising a rotatable casing providing a chamber for material to be ground, said discharge means comprising members defining a channel for receiving material from said chamber, and means defining a slot at the discharge side of said channel, said means comprising a strip of resilient material secured at one edge to one of said channel-defining members, said strip having a substantial portion extending beyond said member and terminating in a free edge in said channel, said portion being freely movable in a direction outwardly from said channel in response to pressure exerted thereon by material within said channel.

5. Discharge means for a grinding mill of the type comprising a rotatable casing providing a chamber for material to be ground, said discharge means comprising members defining a channel for receiving material from said chamber, and means defining a slot at the discharge side of said channel, said means comprising a pair of strips of resilient material each secured at one edge to a corresponding one of said channel-defining members, each of said resilient strips having a substantial portion extending beyond the corresponding channel-defining member and terminating in a free edge in said channel, each of said extending portions of said strips being freely movable in a direction outwardly from said channel in response to pressure exerted thereon by material within said channel.

6. Discharge means for a grinding mill of the type comprising a rotatable casing providing a

chamber for material to be ground, said discharge means comprising members defining a channel for receiving material from said chamber, said channel converging from its receiving side toward its discharge side, and means defining a slot at the discharge side of said channel, said means comprising a strip of resilient material secured at one edge to one of said channel-defining members, said strip having a substantial portion extending beyond said member and terminating in a free edge in said channel, said portion being freely movable in a direction outwardly from said channel in response to pressure exerted thereon by material within said channel, said channel being of sufficient size to enable free movement of grinding elements therewithin.

7. Discharge means for a grinding mill of the type comprising a rotatable casing providing a chamber for material to be ground, said discharge means comprising members defining a channel for receiving material from said chamber, said channel converging from its receiving side toward its discharge side, and means defining a slot at the discharge side of said channel, said means comprising a pair of strips of resilient material each secured at one edge to one of said channel-defining members, each of said strips having a substantial portion extending beyond the corre-

sponding channel-defining member and terminating in a free edge in said channel, each of said extending portions of said strips being freely movable in a direction outwardly from said channel in response to pressure exerted thereon by material within said channel, said channel being of such size as to enable free movement of grinding elements therewithin.

8. Discharge means for a grinding mill of the type comprising a rotatable casing providing a chamber for material to be ground, said discharge means comprising members defining a channel for receiving material from said chamber, and means defining a slot at the discharge side of said channel, said means comprising a strip of resilient material secured at one edge to one of said channel-defining members, said strip having a substantial portion extending beyond said member and terminating in a free edge in said channel, and backing means extending beyond said channel-defining member over a portion of said strip and terminating short of said free edge, the portion of said strip beyond said backing member being freely movable in a direction outwardly from the channel in response to pressure exerted thereon by material within said channel.
